UNITED STATES PATENT OFFICE.

JOSEPH BENOSCH, OF AMSTERDAM, NEW YORK, ASSIGNOR TO KLAUDER-WELDON
DYEING MACHINE COMPANY, OF AMSTERDAM, NEW YORK, A CORPORATION OF
NEW YORK.

APPARATUS FOR DYEING.

1,120,645.

Specification of Letters Patent.

Patented Dec. 8, 1914.

Application filed December 13, 1913. Serial No. 806,373.

To all whom it may concern:

Be it known that I, JOSEPH BENOSCH, a citizen of the United States, residing at Amsterdam, in the county of Montgomery and State of New York, have invented certain new and useful Improvements in Apparatus for Dyeing, of which the following is a full, clear, and exact description, such as will enable others skilled in the art to which 10 it appertains to make and use the same.

This invention relates to dyeing apparatus.

One of the objects thereof is to provide simple and convenient means for facilitating the loading and unloading of a dyeing machine.

Another object is to provide reliable and durable apparatus for locking the parts in operative or active position.

20 Other objects will be in part obvious and in part pointed out hereinafter.

The invention accordingly consists in the features of construction, combinations of elements and arrangement of parts which 25 will be exemplified in the construction hereinafter set forth, and the scope of the application of which will be indicated in the following claims.

In the accompanying drawing, in which 30 is shown one of various possible embodiments of this invention, Figure 1 is an inside elevation of a portion of a carrying member with associated parts; Fig. 2 is a similar view of a portion of Fig. 1, showing the 35 parts in another position; Fig. 3 is a plan view of the parts shown in Fig. 1; Fig. 4 is a diagrammatic elevation of a carrying member with its shaft; and Fig. 5 is a detail view, showing the mounting of a dye stick, 40 certain parts being broken away in order to disclose the structure more clearly.

Similar reference characters refer to similar parts throughout the different views of the drawing.

45 Referring now to Fig. 4 of the drawing, there is shown a rotary carrying member or spider 1, such as is illustrated in my co-pending application, Serial No. 806,372, filed Dec. 13, 1913. As is well known in this art 50 and as is shown in the above application, these members are used in sets of two or more, carrying between them, concentrically with their shaft, sets of yarn-supporting sticks, and it is with the securing means for

these sticks that the leading features of this 55 invention deal.

About the circumferential portion of the carrying member 1 are a series of cups 2, opening outwardly in a radial direction and adapted to support one end of the sticks 3, 60 as illustrated in Fig. 5 of the drawing. The remaining end of these outer sticks is preferably squared, as indicated at 4, and rests within a ratchet-wheel 5, journaled in the companion carrying member 6, which has 65 a general conformation similar to that of the carrying member or wheel 1. The stick 3 may be rotated, as by the star-wheel 7.

Mounted upon the outer portion of wheel 1 are slides 8, each provided with a set of 70 projecting lugs 9, spaced to register with the cups 2. These lugs pass through slots 10, formed in the web of wheel 1, and the slide rests beneath the flange 11 of this wheel. The slots 10 are so proportioned 75 that the lugs may be simultaneously thrown into a position uncovering the sockets, as indicated in Fig. 2, or, on the other hand, may simultaneously cover a plurality of these cups and hold the sticks journaled 80 therein in operative position. The slide is secured in these alternative positions by a set-screw 12, passing through a slot 13 in the web 11, and tapped within the slide as shown in Fig. 5. This set or locking screw 85 serves, when tightened, to clamp the slide against the flange 11. Suitable additional guides, as the pins 14, passing through slots 15, may be provided if desired.

As shown in Fig. 4 of the drawing, each 90 slide preferably extends over a plurality of the cups 2. This figure also illustrates diagrammatically at 16 the inner sticks coacting with sticks 3 in supporting the goods to be dyed.

95 In the operation of this apparatus, the sticks are first inserted within the sockets or cups formed in the ratchet-wheels 5 and are then dropped within the cups 2 at their free ends, the slide being in the position 100 shown in Fig. 2. When the cups, corresponding to a given slide, have received their sticks, the slide is then thrown, by means of the handle of screw 12, into the locking position shown in Fig. 1 and the 105 screw tightened. The sticks 3 are then in position to rotate freely in the cups 2 without chance of accidental displacement and

the use of springs, which may be attacked by the dyeing solution, is obviated.

It is to be noted that the term "lock" is used throughout in a broad sense as indicating the securing of the parts in position.

As many changes could be made in the above construction and many apparently widely different embodiments of this invention could be made without departing from 10 the scope thereof, it is intended that all matter contained in the above description or shown in the accompanying drawing shall be interpreted as illustrative and not in a limiting sense.

15 Having described my invention, what I claim as new and desire to secure by Letters Patent is:

1. In dyeing apparatus or the like, in combination, a pair of rotatable carrying 20 members, a socket upon one of said members, a socket upon the other of said members having an open side, a stick adapted to have one end fitted within said first socket and the other end rest within said second 25 socket, a slide having a projecting portion coacting with said second socket and adapted to be slid on the corresponding carrying member into or out of operative position, and means adapted to secure said slide in 30 operative position.

2. In dyeing apparatus or the like, in combination, a pair of rotatable carrying members, a plurality of sticks rotatably mounted upon said carrying members and 35 positioned between the same and arranged a substantially equal distance from the axis thereof, and a slide upon one of said members coacting with a plurality of said sticks

and adapted to be moved into a position in which it locks the corresponding sticks upon 40 said member against lateral movement when said sticks are in operative position.

3. In dyeing apparatus or the like, in combination, a pair of rotatable carrying members, a plurality of supporting sticks 45 positioned between said members and arranged concentrically about the axis thereof, sockets upon one of said members adapted to receive the corresponding ends of said sticks, sockets upon the other of said members each of which has its outer side open, a slide upon said last carrying member having a plurality of projecting portions adapted with the slide in one position simultaneously to close the corresponding sides of 50 said sockets and hold the corresponding sticks in position, and means adapted to hold said slide in locking position.

4. In dyeing apparatus or the like, in combination, a flanged carrying member 55 having a plurality of sockets thereon open toward their outward sides, a slide secured beneath the flange of said member and having projections thereon passing through slots in said member, said slots being of a 60 length to permit said projections to move into or out of registry with said sockets, and a locking screw passing through said flange and into said slide.

In testimony whereof I affix my signature, in the presence of two witnesses.

JOSEPH BENOSCH.

Washington, D. C."

Correction in Letters Patent No. 1,120,645.

It is hereby certified that in Letters Patent No. 1,120,645, granted December 8, 1914, upon the application of Joseph Benosch, of Amsterdam, New York, for an improvement in "Apparatus for Dyeing," an error appears in the printed specification requiring correction as follows: Page 2, line 36, for the words "a substantially equal distance" read *at substantially equal distances*; and that the said Letters Patent should be read with this correction therein that the same may conform to the record of the case in the Patent Office.

Signed and sealed this 5th day of January, A. D., 1915.

[SEAL.]

R. F. WHITEHEAD,

Acting Commissioner of Patents.
